CLAIM

The ornamental design for a woodsman's wrench, as shown and described.

DESCRIPTION

FIG. 1 is a front isometric view of the woodsman's wrench, which embodies my design;
FIG. 2 is a right side view of the woodsman's wrench;
FIG. 3 is a left side view of the woodsman's wrench;
FIG. 4 is a front view of the woodsman's wrench;
FIG. 5 is a rear view of the woodsman's wrench;
FIG. 6 is a top plane view of the woodsman's wrench; and,
FIG. 7 is a bottom plane view of the woodsman's wrench.
